UNITED STATES PATENT OFFICE.

THOMAS W. WATERS, OF DETROIT, MICHIGAN.

CLAMP.

1,320,590.

Specification of Letters Patent.

Patented Nov. 4, 1919.

Application filed October 28, 1918. Serial No. 260,053.

To all whom it may concern:

Be it known that I, THOMAS W. WATERS, a citizen of the United States, residing at Detroit, in the county of Wayne and State 5 of Michigan, have invented new and useful Improvements in Clamps, of which the following is a specification.

This invention relates to new and useful improvements in clamps of that nature in 10 which the jaw is moved by an eccentric and the principal object of the invention is to provide rollers upon which the eccentric works.

Another object of the invention is to provide a device of this character which is simple and durable in construction, reliable and efficient in operation and one which can be manufactured and placed upon the market at a minimum cost.

20 The invention also consists in certain other features of construction and in the combination and arrangement of the several parts, to be hereinafter fully described, illustrated in the accompanying drawings 25 and specifically pointed out in the appended claim.

In describing my invention in detail, reference will be had to the accompanying drawings wherein like characters denote like 30 or corresponding parts throughout the several views, and in which:

Figure 1 is a side elevation of a clamp supplied with my invention.

Fig. 2 is a section on line 2—2 of Fig. 1. 35 Fig. 3 is a section on line 3—3 of Fig. 1.

As shown in these views the clamp parts are carried by a U shaped member 1, which at its ends is provided with extensions 2. The eccentric 3 is pivoted between said 40 extensions by the pin 4. Said eccentric is provided with the handle part 5 and on one face of said eccentric is provided a flange 6 which is located around the edge thereof.

7 indicates the sliding bolt or jaw of the 45 clamp which engages an opening 8 formed between the ends of the member 1. 9 indicates a circular casing which is connected with the bolt by the screw 10 and said screw

engages a slot 11 formed in the member 1 so that the bolt and casing may have sliding 50 movement in said member. A pair of rollers 12 is journaled in said casing and a part of said casing is cut away as at 13 to receive a portion of the eccentric. The eccentric will project far enough into said 55 casing to engage with said rollers and I keep said rollers in contact with the eccentric by means of a pin 14 carried by a projecting part 15 of the casing, said pin engaging the flange 6 on the eccentric. 60

It will thus be seen that when the eccentric is rotated its periphery will engage the rollers so that a roller bearing is provided and when said eccentric is turned the casing will be forced back so as to project the bolt. 65

It will be seen that the eccentric pin and the screw 10 are in the same plane, practically centering all action, so that the rollers adjust themselves to the eccentric from start to finish of a stroke with or without 70 pressure.

The handle will stay in position under pressure and will not slip or fly back, as is the case of the tools now used. The rollers eliminate friction so that the work is much 75 easier for the workman.

It is thought from the foregoing description that the advantages and novel features of my invention will be readily apparent.

I desire it to be understood that I may 80 make changes in the construction and in the combination and arrangement of the several parts, provided that such changes fall within the scope of the appended claim.

I claim as my invention:

A clamp of the class described comprising a U shape member, an eccentric pivoted in said member and having a flange thereon, a casing slidably mounted in said member and having a cut away portion, bearing rollers in said casing engaging with the said eccentric, a bolt connected with said casing, and a pin on said casing engaging with the flange on the eccentric. 90

In testimony whereof I affix my signature. 95

THOMAS W. WATERS.
